Primary Examiner — Sheryl Lane(74) *Attorney, Agent, or Firm* — Larson & Larson, P.A.; Justin P. Miller; Patrick A. Reid(57) **CLAIM**

The ornamental design for an aquatic conservation cage, as shown and described.

DESCRIPTION

FIG. 1 is a perspective view of an aquatic conservation cage showing the new design; and

FIG. 2 is a right side elevation, which is a mirror image of the left side view thereof;

FIG. 3 is a a is a top planar view thereof; and,

FIG. 4 is a bottom view.

The aquatic conservation cage is an apparatus for the temporary protection of newly planted submerged aquatic vegetation. Typically this vegetation is vulnerable to a variety of aquatic animals including manatees, turtles, and fish. The aquatic conservation cage protects the vegetation until they are mature and able to survive on their own.
